UNITED STATES PATENT OFFICE.

MAXEMILIAN E. KOEHLER, OF SPOKANE, WASHINGTON, ASSIGNOR OF ONE-THIRD TO
JOHN C. MERWIN AND ONE-THIRD TO HENRY KRELLER AND W. S. BENNETT.

APPARATUS FOR MECHANICALLY THROWING A BASE-BALL.

1,152,186.

Specification of Letters Patent.

Patented Aug. 31, 1915.

Application filed March 1, 1915. Serial No. 11,412.

To all whom it may concern:

Be it known that I, MAXEMILIAN E. KOEHLER, citizen of the United States, residing at Spokane, in the county of Spokane and State of Washington, have invented certain new and useful Improvements in Apparatus for Mechanically Throwing a Base-Ball; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in an apparatus for mechanically throwing a baseball.

The primary object of this invention is to provide mechanism, which when set, and subsequently released by an operator, will throw the baseball, the parts being so arranged as to impart a quick, swift movement to the ball.

A further object of the invention is to construct an apparatus for the purpose specified, wherein unusual shocks are absorbed, to prevent undue strain on the parts in the operation.

The invention also comprehends improvements in the details of construction and arrangement of parts which will be herein-after described and particularly pointed out in the claims.

In the accompanying drawings: Figure 1 is a perspective view of the apparatus, the parts being in position to just trip the ball throwing lever to throw a ball. Fig. 2 is an enlarged detail view of the lower end of the ball throwing lever and associated parts. Fig. 3 is an elevation of the apparatus, the parts being in position when the ball is thrown. Fig. 4 is a similar view, the parts being shown in normal position and set to receive a baseball. Fig. 5 is a detail view of the rear end of the frame and part of the resetting mechanism. Fig. 6 is a horizontal section on the line $x-x$ of Fig. 4.

1 indicates a frame composed of two substantially A-shaped members 2-2, flanged at the bottom at 3, to be bolted to a floor or other support, the members being connected by cross bars 4 and 5. On the upper ends

of members 2-2, are mounted bearings 6, 55 which receive trunnions 7, on a throwing arm 8. The outer end of the throwing arm 8, is provided with a baseball cup or holder 9, and located directly below the baseball holder is a catch 10. Extending from one of the trunnions 7, is an angularly disposed crank arm 11, provided at its outer end with an adjustable pin 12, secured in a slot 12^a, in the crank arm, by a nut 13. Pivoted at 14, on one of the cross bars 4, of the frame, are two operating levers 15, and 16. The upper lever 15, is formed with a slot 17, in which fits and slides the pin 12, on the crank arm 11.

The arm 15, is formed with an A-shape 70 frame 18, which has a downward extension 19, provided on its end with a head 20. The companion arm 16, extends downwardly from the pivot 14, and at its lower end is connected a rope 21, to throw a ball in the 75 operation of the apparatus. Extending outwardly from the operating lever 16, is a substantially A-shape frame 23, and from this frame projects an extension 24, formed at its upper end with a buffer 25, which co-operates with the head 20. A stiff coil spring 26, connects the frames 18 and 23, to operate the throwing arm 8, when the levers are turned to spread apart the frames.

Mounted on the rear of the frame 1, and 85 to the support for the apparatus, is a horizontally disposed lever 28, pivoted substantially centrally at 29, and to one end of said lever is attached a rope or chain 22, which at its opposite end is connected to the lower end 90 of the operating lever 16. Pivoted connected to the opposite end of the lever 28, is a plunger rod 30, which operates in a cylinder, pivotally connected at its forward end, as at 32, to the support for the apparatus. The cylinder and plunger rod are provided with the necessary elements to act as a pneumatic cushion to relieve the shock when the apparatus is operated. Also connected to the end of the lever 28, adjacent 95 the plunger rod 30, is a spring 33, which acts to reverse the lever when resetting the apparatus, the cushion formed by the plunger and piston absorbing any shock when the parts are returned by the spring.

On one of the lower cross bars 5, of the frame 1, is a trip lever 35, having its rear end curved upwardly, as at 36, and under

this curved end a pin 37, projecting from the operating lever 16, engages, to trip the ball throwing lever 8. The forward end of the trip lever 35, is formed with a lip 38, which is designed to engage behind the latch 10, on the throwing lever when the parts are set to throw the ball, as clearly shown in the drawings. Located adjacent the bottom of the frame is a chute 40, from the mouth of which extends a spout 41, which delivers a ball to the holder 9, when it is desired to operate the apparatus.

In operation, the spring 33, acting through lever 28, and rope 22, exerts a pull 15 on the lower end of the operating lever 16. The buffer 25, contacting with the head 20, on the upper operating lever 15, causes the two levers to rock on the pivot 14, under the influence of said spring 33. This movement 20 rocks the ball throwing lever through the crank and pin connection 11, and 12, until the catch 10, engages the lip 38, as shown in Figs. 1, 2 and 4. During this operation of setting of the parts, the plunger and 25 cylinder act as a pneumatic cushion to receive the shock incident to the operation of the various levers when same reach the end of their various movements. At this time a ball is introduced into the chute and it rolls 30 down the spout and into the ball holder 9. The ball is now in position, and the parts are set to throw the ball, as shown in Fig. 4.

To trip the mechanism so as to swiftly throw the ball, (assuming the parts are in 35 the position shown in Fig. 4) the operator pulls the cable 21, which rocks the lower operating lever 16, on the pivot 14, until the pin 37, engages the under side of the trip lever 35, and disengages the lip 38, from the 40 catch 10. This movement places the spring 26, under tension and also positions the buffer 25, on the extension 24, to receive the shock of the head 20, on the extension 19, of the upper operating lever 15, as shown in 45 Fig. 1. The operating lever 15, is prevented from rocking on its pivot under the influence of the spring 26, during the preliminary movement of the lever 16, by the catch 10, engaging behind the lip 38, of the trip 50 lever 35. A continued movement of the lever 16, causes the pin 37, to rock the trip lever 35, which disengages the lip 38, from the catch 10, whereupon the spring 26, now under tension, exerts a downward pull on the 55 operating lever 15, which causes the latter to quickly turn on its pivot 14, which movement through the crank 11, and pin 12, imparts a quick swinging movement to the throwing arm 8, and therefore throws the 60 ball out of the holder 9. When the ball is thrown from the holder 9, by the movement just described, the two operating levers 15, and 16, come into alinement with each other, at which time the head 20, of lever 15, contacts with the buffer 25, of the lever 16,

hence the two levers at this time move together. When the lever 16, is moved it pulls the chain 22, and the shock is absorbed by the plunger acting in the cylinder, and spring 33. The parts are now in the position shown in Fig. 3, and are ready to be returned to their normal position upon release of the pull on the rope 21. Immediately the pull on the rope 21 is released, the spring 33 rocks the lever 28, and operating lever 16, and through the buffer 25, and head 20, the lever 15 is rocked, which in turn swings the ball throwing lever on its trunnion to normal position, as shown in Fig. 4.

From the foregoing description it is evident that a ball throwing apparatus is provided, which automatically sets itself to receive the ball to be thrown, and which is so constructed that undue shocks on the various parts, when a ball is thrown, or when the parts are set to throw the ball, is reduced to a minimum. Furthermore, the construction described is such that because of the arrangement of the levers, a quick, speedy movement is imparted to the ball, and notwithstanding the fact that the throwing arm operates rapidly, sudden jar of the parts when the said arm reaches its extreme limit of movements, is dispensed with. If desired, the operating levers 15 and 16, may 95 be mounted between the frame members, but as this change in construction does not alter the improvement from an inventive standpoint, it is not thought necessary to illustrate same.

What is claimed is:—

1. In a ball throwing apparatus, the combination of a frame, a swinging ball throwing arm mounted on the frame, means at the outer end of the arm to receive a ball, a crank on said arm, a pivoted operating lever formed with an extension, a second operating lever pivoted co-extensive with the first mentioned lever and formed with an extension, said extensions forming abutments, a spring between the two levers, a catch for locking the ball throwing arm in set position, means for operating the second mentioned lever to place the spring under tension to throw a ball, and means on said second mentioned lever for disengaging the catch to allow the spring to actuate the arm and throw the ball.

2. In a ball throwing apparatus, the combination of a frame, a swinging ball throwing arm mounted on the frame, means at the free end of the arm to receive a ball, a crank on said arm, an operating lever pivoted to the frame, said lever having an extension, a second operating lever pivoted co-extensive with the first mentioned lever and formed with an extension, the extensions forming abutments, a spring for drawing the abutments together and for operating the ball throwing arm, a catch for holding

- the ball throwing arm in set position, means for operating the second mentioned operating lever to place the spring under tension to throw the ball, means on the second mentioned lever for disengaging the catch to allow the spring to throw the ball, and means for automatically setting the ball throwing arm.
3. In a ball throwing apparatus, the combination of a frame, a swinging ball throwing arm having means to receive a ball, a crank on said ball throwing arm, a pivoted operating lever engaging the crank, a spring attached to the pivoted lever which when placed under tension operates the ball throwing arm to throw the ball, means operating in connection with the operating lever for automatically setting the ball throwing arm, means for holding the ball throwing arm in set position, means for absorbing the shock of the parts when the arm is thrown to set position, and means for releasing the catch to allow the spring to throw the ball.
4. In a ball throwing apparatus, the combination of a frame, a ball throwing arm having means for holding a ball, means for holding the ball throwing arm in set position, means for operating the ball throwing arm, automatic means connected with the latter means for setting the ball throwing arm including a spring and a buffer, and means for tripping the ball throwing arm, said spring and buffer acting to absorb the shock of the parts when the ball is thrown.
5. In a ball throwing apparatus, the combination of a frame, a ball throwing arm mounted on the frame, means including two pivoted operating levers having extensions which normally contact with each other, a spring interposed between said operating levers for operating the ball throwing arm, automatic means coöperating with the two operating levers for setting the ball throwing arm, said automatic means comprising a pivoted lever and a spring between said lever and the frame, a catch for holding the ball throwing arm in set position, and means operated by one of the operating levers for tripping the catch to throw the ball.
6. In a ball throwing apparatus, the combination of a frame, a ball throwing arm mounted on the frame, a crank on the ball throwing arm, an operating lever having a slot which receives the crank, said lever having an extension, a second operating lever pivoted to swing on the same pivot as the first mentioned operating lever and provided with a buffer against which the extension operates, a pivoted resetting lever, a spring connected to the resetting lever, a cushion device connected to said resetting lever, a connection between said resetting lever and the second mentioned operating lever, a catch for holding the ball throwing arm in set position, and a pin on the second men-
- tioned operating lever for operating the catch to cause the first mentioned spring to operate the ball throwing arm to throw a ball.
7. In a ball throwing apparatus, the combination of a frame, a ball throwing element mounted on the frame, means for operating said element to throw a ball including a spring and an operating lever, a catch for holding the ball throwing element in set position, automatic means connected with the operating lever including a buffer and a spring for setting the ball throwing element, and means for moving the operating lever to disengage the catch to cause the first mentioned spring to operate the ball throwing element.
8. In a ball throwing apparatus, the combination of a frame, a ball throwing element mounted on the frame, means for operating said element to throw a ball including a spring and an operating lever, a catch for holding the ball throwing element in set position, automatic means connected with the operating lever including a pivoted lever, a buffer and a spring for setting the ball throwing element, means for moving the operating lever to disengage the catch to cause the first mentioned spring to operate the ball throwing element, and means for introducing a ball to the ball throwing element when the latter is in set position.
9. In a baseball throwing apparatus, the combination of a frame, a ball throwing arm mounted on the frame, a ball support on the end of the arm, a crank on said arm, two operating levers mounted on a single pivot, one of said operating levers having a slot for receiving the crank, said lever having an extension, the other of said operating levers having an extension, a buffer interposed between the two operating levers, a spring between the two levers, automatic setting mechanism connected to one of the operating levers including a spring and pivoted lever, the lever moving when the ball throwing arm is operated in either direction and the spring serving to restore said lever to normal position, a catch for holding the ball throwing arm in set position, and a trip on one of the operating levers for releasing the catch to permit the first mentioned spring to operate the ball throwing arm.
10. In a base ball throwing apparatus, the combination of a frame, a ball throwing arm mounted on the frame, a ball support on the end of the arm, a crank on said arm, two operating levers mounted on a single pivot, one of said operating levers having a slot for receiving the crank, said lever having an extension, the other of said operating levers having an extension, a buffer interposed between the two operating levers, a spring between the two levers, automatic

setting mechanism connected to one of the operating levers including a cushion device, and a spring and pivoted lever the lever moving when the ball throwing arm is operated in either direction and the spring serving to restore the arm to its normal position, a pivoted catch for holding the ball throwing arm in set position, and a pin on the second mentioned operating lever for releasing the catch to permit the first mentioned spring to operate the ball throwing arm.

11. In a ball throwing apparatus, the combination of a frame, a ball throwing arm mounted on the frame, a pivoted operating lever for setting and operating the ball throwing arm, said lever having an extension, a second pivoted operating lever having an extension, a cushion interposed between the extensions a spring between the extensions to operate the ball throwing arm when the second mentioned operating lever is turned on its pivot, a catch to hold the ball throwing arm in set position, means on the second mentioned lever for releasing the catch, and means operating on the second mentioned operating lever to set the ball throwing arm in operative position.

12. In a ball throwing apparatus, the combination of a frame, a ball throwing arm mounted on the frame, a pivoted operating lever for setting and operating the ball throwing arm, said lever having an extension, a second pivoted operating lever having an extension, a cushion interposed between the extensions, a spring between the extensions to operate the ball throwing arm when the second mentioned operating lever is turned on its pivot, a catch to hold the ball throwing arm in set position, means on the second mentioned lever for releasing the catch, and means operating on the second mentioned operating lever to set the ball throwing arm in operative position including a spring and a cushion to relieve the shock when the ball throwing arm is operated in either direction.

13. In a ball throwing apparatus, the combination of a pivoted ball throwing arm, a crank on said arm, a pivoted operating lever having a slot which receives the crank, a catch for holding the ball throwing arm in set position, and means including a spring and a second operating lever for releasing the catch and operating the ball

throwing arm to throw a ball under the influence of said spring.

14. In a ball throwing apparatus, the combination of a pivoted ball throwing arm, a crank on said arm, a pivoted operating lever having a slot which receives the crank, a catch for holding the ball throwing arm in set position, means including a spring and a second operating lever for releasing the catch and operating the ball throwing arm to throw a ball under the influence of said spring, the two operating levers having portions which abut when the ball throwing arm is in set or ball throwing positions, and means connected to the second mentioned operating lever for absorbing the shock when the ball throwing arm is operated.

15. In a ball throwing apparatus, the combination of a ball throwing arm, a catch for holding said arm in set position, means including a pair of pivoted operating levers and a spring between said levers for setting and operating to release the ball throwing arm, connecting means between the ball throwing arm and one of the operating levers, a trip on one of the operating levers to release the catch to cause the spring to turn the other operating lever to operate the ball throwing arm, and a buffer between the operating levers to absorb the shock when the ball is thrown by the ball arm.

16. In a ball throwing apparatus, the combination of a ball throwing arm, two pivotally mounted operating levers for setting and operating the ball throwing arm, a spring between the two operating levers, a catch for holding the ball throwing arm in set position, a trip on one of the operating levers, the operating lever having the trip when turned on its pivot, expanding the spring and when the catch is released said spring operates the other of said operating levers and rocks the ball throwing arm, the said operating levers abutting to limit the movement of the ball throwing arm.

In testimony whereof I have signed my name to this specification in the presence of two subscribing witnesses.

MAX. E. KOEHLER.
